UNITED STATES PATENT OFFICE.

HAROLD B. CRANSHAW, OF WEST NEWTON, MASSACHUSETTS, ASSIGNOR TO CUTTER MANUFACTURING COMPANY, OF EVERETT, MASSACHUSETTS, A CORPORATION OF MASSACHUSETTS.

HINGE ARRANGEMENT FOR FOLDING SCREENS.

Application filed April 9, 1925. Serial No. 21,836.

This invention relates to screens of a type comprising a plurality of sections hinged together to permit folding and more particularly to an improved hinge or pivot connection for the sections of such screens. Screens of the type mentioned are widely used as fire screens. Among the objects of the invention are the provision of a screen of the kind mentioned having improved connections between individual sections whereby the sections may be freely adjusted relative to each other but be maintained always vertical, so that both an improved appearance and a more rigid screen will result.

The preferred embodiment of the invention comprises in general a plurality of substantially rectangular screen sections secured to each other by pivotal connection to pairs of parallel rods which are rigidly mounted at their opposite ends to maintain their axes in a common plane.

In the accompanying drawings, in which certain embodiments of the invention are shown for purposes of illustration,

Fig. 1 is a view of a fire screen in which the invention is embodied;

Fig. 2 is an enlarged fragmentary view with parts broken away to show details of construction;

Fig. 3 is a top plan view of the disclosure of Fig. 2;

Fig. 4 is a bottom view thereof; and

Fig. 5 is a section on line 5—5 of Fig. 2.

In the illustrative embodiment of the invention the individual screen sections 10 are constructed similarly to those disclosed in patent to H. B. Cranshaw et al., No. 1,554,334, Sept. 22, 1925. The frames of these sections preferably consist of sections of rigid metal tubing 11 having their ends cut at an angle of approximately forty-five degrees to form a close fitting union between adjacent sections, and the sections 11 may telescope snugly over the ends of hollow elbow sections 12, to form a solidly reinforced framework as shown at the right-hand side of Fig. 2. The tubing 11 and the elbows 12 are provided with slots 13 to receive a cen-

tral screen 14. The screen 14 as illustrated is formed of a network of wire, but any other suitable material might be used. The edges of this screen are preferably stiffened by metal binding strips 15 which enter the slots 13 when the sections are assembled. The constituent parts of the frames of the individual screen sections may be permanently held in assembled relation by brazing or otherwise, or reliance may be placed upon the means which pivotally connects the screen sections to hold the parts of the individual sections together.

To unite the screen sections 10 to form a folding screen the following construction of joint unit may be employed. The horizontal portions of the elbows 12 and the horizontal tubular sections 11 are drilled to form aligned holes 15' and 16 which are in alignment with the vertical bores of the elbow sections. Through the holes 15' and 16 and the vertical sections 11, cylindrical rods 17 extend, these rods being slightly longer than the vertical dimensions of the screen sections 10. The upper ends of the rods 17 are threaded and screwed into threaded recesses 18 in an elongated head member 19, the distances between the axes of the recesses 18 being preferably just sufficient to allow a narrow clearance between the edges of the sections 10. To prevent rotation of the rods 17 in the recesses 18 and to hold the member 19 rigidly to the rods lock nuts 20 are arranged on the threaded upper ends of the rods and are screwed up hard against the head member 19. The head members 19 may be drilled and tapped for the reception of a threaded element 21 upon which a ball or other ornament 22 may be mounted. The lower ends of the rods 17 are secured in elongated foot members 23. Their rotation in these members may be prevented in any suitable manner, and as illustrated the lower ends of the rods are made square in cross section and enter square holes 24 in the members 23.

In connecting together a pair of sections 10 two rods 17 are first fixed in an upper head member 19 and the rods are then passed

down through the openings 16, 15' and through the interior of the vertical sections 11 and out through corresponding openings 15', 16 at the bottom of the sections 10. A 5 foot member 23 is then placed upon the projecting ends of the rods 17 and brought to a position where it rests closely against the bottoms of the sections 10 while the nuts 20 engage the tops of the latter. The projecting portions of the rods may then be headed over to secure the parts in position, any excess of length being cut off.

10 It will be observed that the rods 17, together with their associated parts, will 15 operate to hold the members 11 and 12 in properly associated relation, without any brazing, sweating, or soldering of the parts together. It will also be noted that since the rods 17 are rigidly secured to the members 19 and 23 and cannot rotate relative thereto, the rods 17 will always remain with their axes in a common plane. This will prevent the screen sections assuming other than vertical positions and will not 20 only result in a neater screen, but preclude any tendency for the screen to fall down or 25 sag due to looseness at the joints.

As shown at the left hand side of Fig. 2 and in Fig. 5, a tube 25 may be provided 30 between the rod 17 and the wire mesh of the screen sections, in which case the wire mesh may or may not be attached to the tube 25 as by spot welding. The tube 25 preferably seats against the inner peripheries of upper and lower frame tubes 11 and 35 may be brazed thereto to add rigidity to the screen section. When using tubes 25 the elbows 12 may be omitted; likewise, the vertical binding strips 15; and the ends of the 40 horizontal binding strips may either be brazed to the tubes 25 or merely abut the tubes. By providing tubes 25 the rods 17 may be more easily inserted without any 45 possibility whatsoever of catching on the wire mesh of the screen section.

I claim:

1. A joint unit for folding sectional screens comprising a pair of rods, and means 50 connecting said rods at their opposite ends whereby movement of one of said rods transmits movement to the other of said rods.

2. A joint unit for folding sectional screens comprising a pair of rods adapted 55 to constitute pivots for adjacent screen sections, and head and foot members receiving said rods at their opposite extremities, said rods being non-rotatively mounted in said head and foot members.

3. A joint unit for folding sectional 60 screens comprising a pair of rods adapted to constitute pivots for adjacent screen sections, a head member threadedly receiving one extremity of each of said rods, lock nuts holding said rods against rotation relative 65 to said head member, a foot member, and

non-rotative connections between the same and the other ends of said rods.

4. A joint unit for folding sectional screens comprising a pair of rods adapted 70 to constitute pivots for adjacent screen sections, a head member threadedly receiving one extremity of each of said rods, lock nuts holding said rods against rotation with respect to said head member, and a foot member having polygonal sockets therein, said rods having their lower extremities polygonal to fit said sockets.

5. A joint unit for folding sectional screens comprising a pair of rods adapted 75 to constitute pivots for adjacent screen sections, a head member threadedly receiving one extremity of each of said rods, lock nuts holding said rods against rotation with respect to said head member, and a foot member having polygonal sockets therein, said rods having their lower extremities polygonal to fit said sockets and being headed over 80 to retain them in said sockets.

6. A joint unit for folding sectional screens comprising a pair of rods adapted to 85 constitute pivots for adjacent screen sections, a head member threadedly receiving one extremity of each of said rods, lock nuts holding said rods against rotation with respect to said head member, and a foot member having polygonal sockets therein, said rods having their lower extremities polygonal to fit said sockets and being headed over 90 to retain them in said sockets, said lock nuts and said foot members being spaced apart 95 a distance substantially the same as the vertical edge dimension of the screen sections.

7. A folding screen comprising sections 100 each having a frame of tubular material comprising tubular elements telescoping with corner elbows, and means for holding said frames together and pivotally connecting said sections including rods traversing certain of said elements and rigidly connected at their extremities.

8. A screen comprising hollow frame members having inside slots to receive the screen material, tubes disposed inside certain of said frame members, and rods extending through said tubes.

9. A screen comprising hollow frame members, tubes disposed in certain of said frame members, and screen material extending 115 into the space between said tubes and frame members.

10. A screen comprising hollow frame members fitted together at beveled joints, and a tube disposed in one of said frame members and having its opposite ends abutting against other of the frame members.

11. A screen comprising hollow frames having slots to receive the screen material, tubular means within said frames for engaging the end of the screen material, rods extending through said tubular means and 120

closely surrounded thereby near each end of the screen, and means interconnecting the ends of the rods.

12. A screen comprising hollow frames having slots to receive the screen material, tubular metal means within said frames for securing the end of the screen material, rods

extending through said tubular means and closely surrounded thereby near each end of the screen, and means rigidly interconnecting the ends of the rods. 10

Signed by me at Boston, Mass. this 31st day of March 1925.

HAROLD B. CRANSHAW.
